UNITED STATES PATENT OFFICE.

PHILIP S. MALONEY, OF PHILADELPHIA, PENNSYLVANIA.

PAVING-TOOL.

SPECIFICATION forming part of Letters Patent No. 288,825, dated November 20, 1883.

Application filed March 20, 1883. (No model.)

To all whom it may concern:

Be it known that I, PHILIP S. MALONEY, of the city and county of Philadelphia, and State of Pennsylvania, have invented an Improvement in Paving-Tools, set forth in the following specification.

My invention has reference to street-paviors adapted to hammer street-stones into solid positions; and it consists in certain improvements in the construction of the same, as fully set forth in the following specification, and shown in the accompanying drawings, which form part thereof.

In the drawings, Figure 1 is an elevation of my improved paviors. Fig. 2 is a vertical section of same. Fig. 3 is a plan view, looking up from the bottom; and Fig. 4 is a perspective view of the clamping and retaining band.

A is the cylindrical wooden body, terminating at the top in a handle, B. About half way down the body is provided with one or more holes, D, into which the horizontal handle C is secured. By having more than one of said holes the said handle may be adjusted to suit men of various height. The lower end, A', of the body is turned down to form a shoulder, e, and the clamping-band E of iron or steel is placed thereon. This band E is made conical on its outside to increase its strength at the bottom and give more striking-surface, and is provided with a light flange or lugs, F, at its top, the same being set into the body, as shown, and secured in place by rivets f. By this means it is impossible for the retaining-band E to work off the body, and thereby ruin the tool. The band E extends some distance below the bottom of the body, leaving a space, H, which is filled in with pointed metallic pieces, which are driven into the wood. First, a circle of conical or tapering metal pieces, I, are driven into the bottom of the body and

close to the band E. Then a second row of similar metal pieces are driven into place, and finally the whole of them are made tight and firm by means of a central wedge or cone, G. 45 This metal filling I G may be made in various ways; but I prefer that shown.

I do not limit myself to the exact construction shown, as it may be modified in various ways without departing from my invention. 50

I am aware of Patent No. 162,384, to Hitchcock, and claim nothing therein shown or described, the device therein shown differing from mine, in that there are no loose wedge-fitting pieces I G, which are forced within the 55 band E, tending to expand it, and he has no extensions F on his band to hold it in place on the body.

Having now described my invention, what I claim as new, and desire to secure by Letters 60 Patent, is—

1. The body A, provided with handles, in combination with retaining-band E, having extensions F, rivets f, and metal filling, substantially as and for the purpose specified. 65

2. The body A, provided with handles B and C, band E, having extensions F, rivets f, and conical or tapering filling-pieces I G, substantially as shown and described.

3. The cylindrical wooden body A, having 70 handles B and C, band E, made conical on the outside and extending below the body, and having extensions F, rivets f, and filling-pieces I G, the said band and extensions being set into the body to bring their outer surfaces 75 flush therewith, substantially as shown.

In testimony of which invention I hereunto set my hand.

PHILIP S. MALONEY.
